UNITED STATES PATENT OFFICE.

FLETCHER K. BOHRER, OF MAROA, ILLINOIS.

DESIGN FOR AN ICE-CRUSHER.

SPECIFICATION forming part of Design No. 32,230, dated February 13, 1900.

Application filed January 20, 1900. Serial No. 2,213. Term of patent 7 years.

To all whom it may concern:

Be it known that I, FLETCHER K. BOHRER, of Maroa, in the county of Macon and State of Illinois, have invented and produced a Design for an Ice-Crusher, of which the following is a specification.

In the drawings forming part of this specification, Figure 1 is an elevation of the ice-crusher. Fig. 2 is a plan of the upper surface of the device. Fig. 3 is a plan of the under surface.

The essential peculiarities of the design are the base or body 1, square in plan and having a pyramidal upper surface 2, which merges into a vertical cylinder 3. The han-

dle 4 continues the circle of the socket-cylinder 3, tapering slightly toward its upper end, and the under surface of the base has a set of downwardly-projecting pyramidal teeth 5, disposed in rows parallel with the sides of the base.

What I claim is—

The design for an ice-crusher as herein shown and described.

In testimony whereof I sign my name in the presence of two subscribing witnesses.

FLETCHER K. BOHRER.

Witnesses:

N. B. STOUTENBOROUGH,
S. A. FRIEDMAN.
